UNITED STATES PATENT OFFICE.

CLEMENT COLERIDGE CLAWSON, OF NEWARK, NEW JERSEY.

KALEIDOSCOPE.

SPECIFICATION forming part of Letters Patent No. 416,092, dated November 26, 1889.

Application filed August 26, 1889. Serial No. 321,966. (No model.)

To all whom it may concern.

Be it known that I, CLEMENT COLERIDGE CLAWSON, a citizen of the United States, residing at Newark, in the county of Essex and State of New Jersey, have invented certain new and useful Improvements in Kaleidoscopes, of which the following specification is a full, clear, and exact description.

This invention relates to kaleidoscopes, which in general, as is well known, consist substantially of a tube or case provided with a sight-opening at the front end, mirrors or reflectors arranged at a suitable angle to each other in said tube or case, a movable object-box so arranged that the objects therein will be reflected in said mirrors, and means for enabling the interior to be illuminated from a convenient source, such source being most commonly (if not universally heretofore) the diffused light of a room, and the ordinary means for enabling the interior of the instrument to be illuminated, consisting in the use of transparent or translucent glass for the back and front of the object-box (which covers the open rear end of the mirror-tube) and the support of said box, so as to give the light access to the glass back of said box. Some of the improvements, however, may be used in other connections.

The present invention consists, principally, in a new or improved kaleidoscope having a power mechanism for automatically moving the object box or holder, in which kaleidoscope normally there is neither movement of the said object-holder by the power mechanism nor the ability to observe the objects or their reflection by a person desiring to use the instrument, (or if either of these exists it is only to a limited extent,) but in which on the introduction of one or more coins or tokens, with or without the performance of other intelligent operation by the person using the instrument, (or other person present,) the object-holder is moved automatically at a suitable speed by the appropriate power, (which may be that of any suitable agent, as a weight, a spring, electricity, magnetism, air, water, or other convenient medium,) and sight into or through the instrument is permitted or a brighter view of its interior is furnished during the whole or a part of the time said object-holder is in motion.

In this new or improved kaleidoscope, in addition to the angularly-arranged mirrors, the object-box, the tube or case provided with a sight-opening, and the means for enabling the interior of the instrument to be illuminated, which severally or collectively may be of any ordinary or suitable form and arrangement, the following elements are employed, namely: first, a light-controller (such as a screen, for instance, or a means for varying a source of light) for cutting off or permitting the illumination of the instrument or the passage of the rays of light out of or through the same, according to the position of said light-controller; second, a power mechanism (such as a clock-work, electric motor, or the like) for automatically moving said object-holder, in contradistinction to a handle or handles, and connections for operating said holder by the person using the instrument; third, a movement-controller of any known or suitable description (such as a movable stop-pin, a shifting clutch, a switch, or the like) for stopping or permitting the movement of said object-holder by the power mechanism, according to the position of said movement-controller, and, fourth, a coin-motor composed of any ordinary or suitable device or devices to be actuated or influenced by the coins or tokens introduced, connected directly or indirectly with the said light and movement controllers, or either of them, so that the shifting of one or both of said controllers from the normal to what may be called the "active" position is dependent upon the action or influence of one or more suitable coins or tokens on said coin-motor. Of course if only one of these controllers, as the light-controller or the movement-controller, be connected with the coin-motor, a certain use might be made of the instrument without payment for the diversion which might thus be secured, yet payment would still be necessary to the full use and enjoyment of the instrument. It is, however, preferred to connect both controllers with the coin-motor.

It is evident that the elements mentioned might be connected with one another in various ways in order to accomplish the new result before described. For example, it is a possible arrangement, but one not essential to

said result, that the sight-controller should be shifted by the power mechanism (or one connected therewith) and the coin-motor be arranged first to act upon or influence the movement-controller and indirectly through the movement-controller and the power mechanism to act upon or influence the light-controller.

Although, as already stated, the invention consists, principally, in a new or improved kaleidoscope composed of the elements mentioned, in which either the light-controller or the movement-controller, or both, are connected with the coin-motor, yet the invention also extends beyond these limits, for useful combinations (new, as I believe, with myself) of a number of elements less than the whole may be made—as, for example, if the coin-motor should be omitted, or if the light-controller and coin-motor should be employed in a kaleidoscope with an object-holder to be moved by hand, or if the light-controller should be omitted, the other elements remaining, as hereinbefore specified, or if the movement-controller and coin-motor should be applied to an object-box to be rotated by hand. Moreover, so far as I am aware, a kaleidoscope whose use is entirely or in part dependent on the introduction of one or more coins or tokens has never been produced before my invention thereof.

The invention also consists in the combination of a music-box or automatic musical instrument with the elements (or some of them) of the new or improved kaleidoscope, as hereinbefore specified, so that tunes are played at the same time that the moving objects and their reflections are exhibited.

Further, the invention comprises certain special improvements or particular constructions, combinations, and arrangements of parts, as hereinafter particularly pointed out, for all the uses to which such parts, improvements, or combinations are or may be adapted.

In the accompanying drawings, which form part of this specification, Figure I is a front elevation of an instrument (or machine) constructed in accordance with this invention, the door of the hollow stand being opened to expose the interior. Fig. II is an end elevation of the same instrument, (or machine.) Fig. III is a front elevation, on a larger scale, partly in vertical longitudinal section, the cover and also a portion of the front of the stand being removed. Fig. IV is a partial view in plan and horizontal section. Fig. V is a partial view in vertical cross-section on line *v* of Figs. I and III. Fig. VI is a partial view in vertical longitudinal section on line *vi* of Fig. II. Fig. VII is a back view of certain division-strips and other parts inside the object-box. Figs. VIII and IX are detail views showing another disposition of the division-strips. Fig. X is a partial view in end elevation (partly broken away,) illustrating another form of light-controller from that shown in prior figures. Figs. XI and XII are detail views

illustrating a third form of light-controller, and Fig. XIII is a detail view in perspective of a portion of the cover of the instrument. 70

As shown, the mirrors A A' of the kaleidoscope (see Figs. III and V) are set in a horizontal cylindrical tube B, having at its rear end the object-box C, which is movable about a horizontal axis. The tube B is supported 75 at the front end by the cap-piece 2, provided with a contracted front portion with a sight-opening therein and mounted on the front standard 4, and at the rear end by the ring 5, fastened to the overhanging arm of the rear standard 6. The mirrors A A' are, as shown, long strips of silvered glass placed lengthwise of the tube B at a suitable angle to each other. They are so arranged in connection with a third strip A'' as to form a hollow or 80 tubular figure triangular in cross-section, the third strip A'' being preferably also a mirror, although it need not be. The three strips are of such width that the hollow figure formed thereby nearly fills the bore of the 85 tube B, and they are wrapped with paper 7 or other tissue or fibrous wrapping material, so as quite to fill said tube. This wrapping 7 holds the strips firmly and forms a packing between the glass of the mirrors and the 90 inclosing-wall of the tube and acts as a buffer to said glass. This mode of securing the mirrors in place is only a subordinate feature and is not essential to the invention.

The object-holder C consists of a box whose 100 side walls are formed by the cylindrical shell 8, and whose front and back consist of the glass plates 9 and 10, respectively, the front 9 being of plain transparent glass and the back 10 of ground glass, as common in 105 kaleidoscopes. In the box C are loose objects D D', of colored glass or what not, and also objects D'', fixed to the object-holder. The interior of the box is divided by longitudinal 110 divisions 11, preferably of plain glass, and different sets of the loose objects are placed in the different compartments. Two arrangements of these divisions are illustrated—one in which they are of trapezoidal form and extend obliquely from front to back, as shown 115 in Figs. III, V, and VII, and the other in which they are rectangular and lie at right angles to said front and back, as shown in Figs. VIII and IX. With the arrangement of Figs. II, 120 V, and VII a passage is left around the divisions 11 for the outer set D' of loose objects to travel; but in Figs. VIII and IX the peripheral compartments are separate and are each provided with a set D' of loose objects. The oblique arrangement of the divisions 11 125 tends to cause the loose objects D to pass forward under the action of gravity against the front 9 of the object-box. In both arrangements there are central and peripheral compartments of angular outline; but other arrangements of longitudinal partitions could be made, an object-box rotating about a horizontal axis and divided longitudinally into compartments being new generally.

The fixed objects D'' are preferably strips of colored glass. As shown, they are confined between the edges of the divisions 11 and the box-front 9, which latter is confined by a screw-ring 12, while the box-back 10 is pressed against a shoulder 13 on the shell 8. This shell at its front end fits into the ring 5, in which it is free to turn, and is fastened to a hemispherical shell or hood 14, which is journaled on the stationary journal-pin 15, fixed in the standard 6, the two shells 8 and 14 being preferably cast in one piece. By rotating the shell 14 about the journal-pin 15 the object box or holder C is of course moved so as to alter constantly the position relatively to the mirrors A A' of the objects belonging to said holder. The use of the longitudinal divisions, as also the use of fixed objects in connection with loose objects, gives a variety of new effects.

The means shown in Figs. III and V for enabling the interior of the instrument to be illuminated consist of an incandescent electric lamp E, mounted in the shell 14 on the end of the pin 16, of insulating material, fixed in the journal-pin 15, which is made hollow for its reception. The conductors 17 and 18 extend through the pin 16 for supplying current from a suitable source of electricity, as the galvanic cells 19. So long as proper current flows through the lamp it glows and illuminates the interior of the instrument, and on the interruption of the current the said interior is left in darkness, the shell 14 being opaque. It is preferred to place a reflector 21 around the lamp E and to form the said reflector of trapezoidal pieces of silvered glass confined between the ground-glass plate 10 and the hub 22 inside the shell 14, the space back of the reflector being filled with paper or other packing. This use of an electric lamp as an illuminator for kaleidoscopes is advantageous because of the bright illumination, and also because by placing said lamp in line within the space between the mirrors A A' its light is reflected back and forth by the mirrors, so as to produce very brilliant new effects. It may appear as a part of the kaleidoscopic figures, either in its natural appearance (by making the back plate 10 of plain glass) or modified more or less by the character of the medium through which its rays are transmitted.

The object-box C is moved by means of mechanism driven by the weight G, suspended in loops of the wire 23, which is fastened at one end to the stationary cross-piece 24, Figs. I and III, runs over the pulleys 25 and 26 on said weight and said cross-piece, respectively, and is wound at its other end upon the drum 27, said drum being mounted on a shaft 28 with a spur-wheel 29, which meshes into a spur-pinion 30, fixed to the shell 14. As the weight runs down it of course unwinds the wire 23 from the drum 27, rotating the shaft 28, spur-wheel 29, pinion 30, shell 14, and object-holder C. The descent of the weight is

moderated by means of a fly 31, Fig. II, forming part of an automatic musical instrument H H', which it is preferred to combine with the kaleidoscope, so as to furnish music during the exhibition of the kaleidoscope. The musical instrument shown is the ordinary music-box with toothed cylinder and comb. The cylinder is driven from the drum 27 through the gears 55 and 56.

The movement-controller for the object-box consists, as shown, of a movable stop I, which is normally in the path of the tooth 32, rotating with the cylinder H of the musical instrument, but which, being mounted on a lever-arm 33, is moved out of the way of said tooth when desired to allow the music-cylinder H and the object-box C to be moved by the weight G.

The coin-motor shown consists of a lever K, having its lower end provided with a plate 34 in line with a coin-spout K' and being free to move under the impact or weight of a coin directed onto said plate by the spout K'. It is connected with the movement controller or stop I, the arm 33, which carries said stop, being, as shown, a continuation of lever K, so that the movement of said lever K under the action of a coin withdraws the stop I or shifts the movement-controller in the direction to start the movement of the music-cylinder H and the object-holder C. As shown, the coin drops off the plate 34 almost immediately and falls into the money-drawer 35 below, and the lever K is so hung that so soon as the pressure of the coin is relieved it returns to normal position and the stop I is interposed again in the path of the tooth 32, so as to arrest the movement of the object-holder C and the music-cylinder H so soon as the latter has completed a revolution.

The light-controller (shown in Figs. I to V) consists of a circuit-changer or electric switch L L', Fig. V, composed of a notched disk L and a contact-spring L' and arranged in the circuit of the lamp E, and it is connected with the coin-motor K K' by having the notched disk L fixed on the end of the music-cylinder H, so as to be rotated by the weight G when the stop-pin I is removed by the action of the coin on the lever K of the coin-motor as just explained. The notched disk L of the light-controller is in electrical connection with the lamp E, through the frame 36 of the musical instrument, and the spring L', insulated from the said frame by being secured to the wooden sounding-board of the musical instrument, is connected electrically with the portion of conductor 17 leading to the cells 19. Normally the end of the spring L' is out of electrical connection with the disk L; but as soon as the latter revolves a short distance it makes contact therewith and establishes the light in the shell 14. At the end of a revolution of the disk L the electrical connection is interrupted and the light of the lamp E ceases, leaving the interior of the instrument in darkness.

The sounding-board is made of two boards 37 and 38, connected and spaced by the strips 39, the upper board being cut away in the middle (see Figs. IV and V) to receive the frame 36, which rests on the strips 39. The sounding-board forms the top of the stand M of the instrument.

The instrument is covered by a glass case N, which is formed of glass sides and ends 40 and angle-strips 41 at the edges. These angle-strips are fastened together at their junctions by corner-pieces 42, (see Fig. XIII,) having for each angle-strip a branch or arm, to which said strip is secured by solder or otherwise. The glass sides and ends are confined between the angle-strips 41 and holding-strips 43, secured by screws or otherwise to the respective arms or branches of the corner-pieces 42. This case is adapted to the inclosed instrument, and the glass of one end is arranged to cover the sight-opening in the cap-piece 2. (See Fig. VI.) Said end is also preferably provided for an eye-plate 44, the face of which may be utilized for directions in regard to the use of the instrument.

If during the use of the instrument the weight G should reach the end of its course, it is evident that the lamp E would continue to glow, since the spring L' would still make contact with the disk L. To avoid such result a circuit-breaker P P' is placed in one of the conductors, as 18, of the lamp E and is arranged to be operated to break the circuit when the power to drive the moving parts of the machine is nearly or quite exhausted. As shown, the spring P is placed in the path of the weight G and normally makes contact with the contact-plate P'; but when the weight G is approaching the bottom of its course said spring is pressed down by said weight and moved off the plate P', so as to break the circuit and extinguish the lamp E, although the spring L' may still make contact with the disk L. When the weight G is lifted again in rewinding the same, the spring P moves itself automatically back into contact with the plate P'.

In Fig. X a light-controller is shown in the form of a screen or shutter L'', which normally interposes itself on the inside of the case N over the sight-opening in the cap-piece 2, so as to prevent the light-rays from passing out of or through the instrument. As shown, it is mounted on a lever 45, fulcrumed at the lower end and resting at a higher point against a stationary pin 46. A pin 47 projects from the arm 33 of the movement-controller behind the lever 45, but preferably at such a distance that the stop I may clear the tooth 32 just before the pin 47 strikes the lever 45. In this arrangement the music-cylinder H is provided with a cam-surface 48, which moves out the stop I, arm 33, pin 47, and lever 45, so as to remove the screen or shutter L'' from before the sight-opening in the cap-piece 2 and hold the parts in this position until the music-cylinder has nearly

completed a revolution, when the said cam-surface allows the shutter L'' to drop, so as to close the sight-opening, and the stop I to place itself in the path of the tooth 32 in position to stop the mechanism driven by the weight G. With this form of light-controller the electric lamp E or an opening behind the object-box for the passage of light from an outside source could be used to enable the interior of the instrument to be illuminated.

In Figs. XI and XII a light-controller is shown in the form of a screen or shutter L''' at the rear end of the machine, which prevents the passage of light into or through the instrument. This screen or shutter is formed on the shell 14, which is elsewhere perforated with slots 49 for the passage of light, and which is covered by a stationary casing L''', of opaque material, provided with an opening 50 for the passage of light from any suitable source, natural or artificial. Normally this opening is closed by the screen or shutter L''', so that the interior of the instrument is in darkness. When, however, the power mechanism is started through the action of a coin on the lever K of the coin-motor and the consequent shifting of the stop I or movement-controller, the rotation of the shell 14 removes the screen or shutter L''' and brings the slotted portion of said shell opposite the opening 50, so that light may stream through that opening and the slots, which thus enable the interior of the instrument to be illuminated.

I make no claim herein to the construction of the glass case, as the same has been adjudged to be subject-matter for a separate application.

105

I claim as my invention or discovery—

1. A new or improved kaleidoscope comprising, in combination with a tube or case provided with a sight-opening, angularly-arranged mirrors, a movable object-holder, and means for enabling the interior of the instrument to be illuminated, a light-controller for exhibiting the interior of the instrument and for closing the exhibition according to the position of said controller, a power mechanism for driving the said object-holder, a movement-controller for starting and stopping the motion of the said object-holder by said power mechanism, and a coin-motor connected with either or both said light and movement controllers, substantially as described.

2. A new or improved kaleidoscope comprising, in combination with a tube or case provided with a sight-opening, angularly-arranged mirrors, a movable object-holder, and means for enabling the interior of the instrument to be illuminated, a light-controller for exhibiting the interior of the instrument and for stopping the exhibition, a power mechanism for driving said object-holder, and a movement-controller for starting and stopping the motion of the said object-holder by the power mechanism, substantially as described.

3. In combination with the angularly-ar-

ranged mirrors and tube or case of a kaleidoscope, the movable object-holder, the means for enabling the interior of the instrument to be illuminated, and means whereby the said 5 object-holder can be moved, a movement-controller for the said object-holder, and a coin-motor connected with said movement-controller, substantially as described.

4. The combination, with the tube or case 10 and angularly-arranged mirrors in a kaleidoscope, of a rotary object-box with transparent or translucent front and back, a power mechanism for revolving said object-box, a movement-controller for starting and stopping 15 the rotation of the said object-box by said power mechanism, and a coin-motor connected with said movement-controller, substantially as described.

5. The combination, with the tube or case 20 provided with a sight-opening, the angularly-arranged mirrors, and the transparent or translucent object-box, of an electric lamp arranged on the opposite side of said box 25 from said mirrors in line with the opening between said mirrors, substantially as described.

6. The combination, with a tube provided 30 with a sight-opening and angularly-arranged mirrors, of the cup-shaped shell, a journal-bearing for said shell, means for revolving the said shell, and the object-holder mounted in front of and turning with said shell, substantially as described.

7. In combination with a kaleidoscope-tube 35 provided with angularly-arranged mirrors, a transparent or translucent object-box, a cup-shaped shell behind said box, and an electric lamp in said shell, substantially as described.

8. In combination with a kaleidoscope-tube 40 provided with angularly-arranged mirrors and an object-box, the rotary shell on which the object-box is mounted, the stationary journal-pin on which said shell turns, and an electric lamp mounted on said pin in said 45 shell, substantially as described.

9. The combination of the tube provided with the angularly-arranged mirrors, the object-box, the electric lamp, and the cup-shaped shell provided with a reflector inclosing said 50 lamp, substantially as described.

10. The cup-shaped shell provided with a central hub on the inside and a reflector formed of numerous trapezoidal pieces with the narrow ends resting on the said hub and 55 their wide ends supported at the mouth of the shell, substantially as described.

11. In combination with a kaleidoscope 60 provided with angularly-placed mirrors, a rotary object-box mounted on a horizontal axis, or axis having a horizontal component, and divided longitudinally or in the direction of said axis, and provided with different sets of loose objects in the compartments thus formed, substantially as described.

65 12. In combination with a kaleidoscope-tube provided with angularly-arranged mirrors, an object-box mounted on a horizontal

axis of rotation and divided longitudinally by partitions arranged to form a hollow figure in the center of said box and provided with 70 loose objects inside and outside the walls of said figure, substantially as described.

13. In combination with a kaleidoscope-tube 75 provided with angularly-arranged mirrors, a rotary object-box provided with objects fixed in position on the object-box and objects loose in said box, substantially as described.

14. In combination with the angularly-arranged mirrors and tube of a kaleidoscope, a 80 movable object-holder, means for moving said holder, and means for illuminating the interior of the instrument, a light-controller for exhibiting the moving objects belonging to said holder and their reflection in said 85 mirrors and for stopping the exhibition, according to its position, and a coin-motor connected with said light-controller, substantially as described.

15. The combination of a kaleidoscope-tube 90 provided with angularly-placed mirrors, a rotary object-box at the rear end of said tube, an electric lamp for illuminating the interior of the said object-box and tube, a light-controller in the form of a circuit-changer or 95 electrical switch in the circuit of said lamp, and a coin-motor connected with said circuit-changer or electrical switch, substantially as described.

16. The combination, with the angularly-arranged mirrors and tube in a kaleidoscope, a movable object-holder therefor, and means 100 for illuminating the interior of the instrument, of a power mechanism for driving said object-holder, a movement-controller for 105 starting and stopping the movement of said object-holder by said power mechanism, a coin-motor connected with said movement-controller, and a light-controller for exhibiting the interior of the instrument and for stopping 110 the exhibition connected with said power-mechanism and through it with the coin-motor, so as to be controlled thereby, substantially as described.

17. The combination of the tube and angularly-arranged mirrors in a kaleidoscope, a movable object-holder therefor, means for illuminating the interior of the instrument, a power mechanism for driving said object-holder, a movement-controller for starting 120 and stopping the movement of the said object-holder by said power mechanism, a musical instrument operated by said power mechanism, and a light-controller for exhibiting the interior of said instrument and stopping 125 the exhibition, according to the position of said light-controller, substantially as described.

18. The tube provided with a sight-opening 130 and with angularly-arranged mirrors and the rotary transparent or translucent object-box at the rear end of said tube, in combination with a music cylinder and comb, gearing connecting the said cylinder with the

said object-box, a weight or source of power for driving the music-cylinder and object-box, a movement-controller for starting and stopping said music-cylinder and object-box, and a coin-motor connected with said movement-controller, substantially as described.

19. The combination, with an electric lamp, a circuit-changer or electrical switch in the circuit of said lamp, and a power mechanism connected with said circuit-changer, of a supplemental circuit-breaker in said circuit, the same having a part which is shifted to open the circuit when the power for operating said mechanism runs down, substantially as described.

20. The combination, with the tube provided with a sight-opening and with angularly-arranged mirrors and the movable object-holder, of an electric lamp, a power mechanism for driving said object-holder, a movement-controller, a circuit-changer or electrical switch in the lamp-circuit operated by said power mechanism, and a supplementary circuit-breaker in said lamp-circuit, the said circuit-breaker having a part which is shifted to open the circuit when the power mechanism is run down, substantially as described.

21. The stand provided with a sounding-board on top, the musical instrument mounted on said sounding-board, the tube with a sight-opening and angularly-arranged mir-

rors supported above said musical instrument, the rotary object-box at the rear end of said tube, the gearing connecting the music-cylinder with the rotary object-box, and a movement-controller for starting and stopping the mechanism, substantially as described.

22. A coin-controlled musical self-exhibiting kaleidoscope comprising, in combination with the kaleidoscope tube or case, the angularly-arranged mirrors, object-box, and means for enabling the interior of the instrument to be illuminated, the following additional elements, namely: a musical instrument, a power mechanism connected with the cylinder of said instrument and said object-box, a movement-controller, a light-controller, and a coin-motor, substantially as described.

23. In combination with the tube provided with a sight-opening and angularly-arranged mirrors of a kaleidoscope, an object-box mounted to turn on a horizontal axis and provided with a compartment of an angular outline and loose objects therein, substantially as described.

In testimony whereof I have signed this specification in the presence of two witnesses.

CLEMENT COLERIDGE CLAWSON.
